CLAIM

The ornamental design for a motorcycle turn signal lens, as shown and described.

DESCRIPTION

FIG. 1 is a perspective view of the motorcycle turn signal lens.

FIG. 2 is a front elevational view of the motorcycle turn signal lens.

FIG. 3 is a side elevational view of the motorcycle turn signal lens with the opposite side being a mirror image of the same.

FIG. 4 is a top plan view of the motorcycle turn signal lens with the bottom being a mirror image of the same; and, FIG. 5 is a perspective view of the motorcycle turn signal lens installed in a bullet housing.

The back forms no part of the claimed design.

The broken lines form no part of the claimed design.
